ARCHIE MACPHAIL NIVEN, OF DETROIT, MICHIGAN, ASSIGNOR TO CONTINENTAL MOTORS CORPORATION, OF DETROIT, MICHIGAN, A CORPORATION OF VIRGINIA

SLEEVE-VALVE-DRIVING MECHANISM

Application filed August 13, 1928. Serial No. 299,212.

This invention relates to internal combustion engines of the "Burt-McCollum" sleeve valve type in which a single sleeve is moved in a combined reciprocating and oscillating path. More particularly my invention provides an improved driving mechanism for the sleeve.

In general my invention comprises a multi-armed driving element actuated by the valveshaft, one arm of the element connected with the sleeve and another arm being guided so as to impart to the sleeve a closed curve path. One important advantage of my improved drive resides in the movement imparted to the sleeve, the movement being in the form of a symmetrical figure affording ready computing and laying out of the cylinder and sleeve ports for performing the usual valving functions of the engine.

A further feature of my invention resides in the provision of a simple driving mechanism which may be manufactured cheaply and assembled readily.

Referring to the drawings which illustrate an embodiment of the invention,

Fig. 1 is a sectional elevation view through a typical cylinder of the engine showing the sleeve driving mechanism,

Fig. 2 is a fragmentary plan view partly in section showing the valveshaft driving a plurality of sleeves,

Fig. 3 is a detail elevation view of the sleeve driving element, and

Fig. 4 is a diagrammatic view illustrating the path of movement of the driving element at its point of connection with the sleeve.

Reference character A represents the engine having one or more cylinders 10, cylinder head 11 with spark plug opening 12, and cylinder intake and exhaust ports 13 and 14. The usual crankshaft 15 is located in crankcase 16 and is actuated by connecting rod 17 and piston 18, the parts associated with one typical cylinder being described and illustrated for convenience.

Located co-axially with the cylinder and preferably intermediate the cylinder 10 and piston 18 is a sleeve valve B having a lower portion projecting into the crankcase for receiving the drive and an upper portion pro-

vided with ports 19 for cooperation with the cylinder ports 13 and 14. The particular form and arrangement of ports forms no part of this invention and they may have the usual well known construction.

A valveshaft C is located preferably to one side of the sleeves B and is rotatable in spaced bearings 20. The valveshaft is driven as usual for a four stroke cycle engine at half crankshaft speed by any suitable driving means 21. The valveshaft C has spaced cranks 22, each crank operating the sleeve driving element D. The element D has a bearing 23 and associated bearing cap 24 engaging crank 22, the main body portion of the element further being constructed substantially L-shaped, one arm 25 extending substantially horizontally and inwardly toward the sleeve B and the other arm 26 extending substantially vertically and preferably downwardly for convenience into the crankcase 16.

The arm 25 carries a laterally projecting pin 27 slidable in ball 28 to permit rotational movement of the sleeve. Ball 28 is movable in socket 29 carried in the sleeve driving lug 30. The arm 26 is pivoted by a pin 31 to a pin 32 which is guided for reciprocation in a bearing 33 conveniently carried inwardly from the crankcase 16.

In operation the valveshaft C is driven from crankshaft 15, each crank 22 moving the driving element D so as to impart the combined movement to sleeve B. Referring to Fig. 4 the pin 27 is moved in a substantially symmetrical elliptical path 34 which may be varied to more nearly approach a circle as desired by varying the lengths of arms 25, 26. Thus any point on the sleeve will trace a closed curve symmetrical path on the cylinder substantially as indicated at 34.

What I claim as my invention is:

1. In an internal combustion engine, a cylinder ported for intake and exhaust, a piston reciprocating within the cylinder, a crankshaft driven from the piston, a sleeve valve co-axial with the cylinder and ported for cooperation with the cylinder ports, a valveshaft driven from the crankshaft, and a rigid substantially L-shaped driving element transmitting the drive from the valveshaft to the

sleeve for imparting thereto a combined reciprocating and oscillating movement.

2. In an internal combustion engine, a cylinder ported for intake and exhaust, a piston reciprocating within the cylinder, a crankshaft driven from the piston, a sleeve valve co-axial with the cylinder and ported for cooperation with the cylinder ports, a valveshaft driven from the crankshaft, a multi-arm driving element transmitting the drive from the valveshaft to the sleeve for imparting thereto a combined reciprocating and oscillating movement, one arm of said element extending substantially vertically with respect to a horizontal plane containing the valve shaft axis, and means guiding movement of the last said arm.

3. In an internal combustion engine, a cylinder ported for intake and exhaust, a piston reciprocating within the cylinder, a crankshaft driven from the piston, a sleeve valve co-axial with the cylinder and ported for cooperation with the cylinder ports, a valveshaft driven from the crankshaft, a multi-arm driving element transmitting the drive from the valveshaft to the sleeve for imparting thereto a combined reciprocating and oscillating movement, one arm of said element extending substantially horizontally of the engine for connection with the sleeve, and another arm of said element extending substantially vertically of the engine.

4. In an internal combustion engine, a cylinder ported for intake and exhaust, a piston reciprocating within the cylinder, a crankshaft driven from the piston, a sleeve valve co-axial with the cylinder and ported for cooperation with the cylinder ports, a valveshaft driven from the crankshaft, a multi-arm driving element transmitting the drive from the valveshaft to the sleeve for imparting thereto a combined reciprocating and oscillating movement, one arm of said element extending substantially vertically, means guiding movement of the last said arm, a guide element pivotally connected to the last said arm, and a bearing for said guide element.

5. In an internal combustion engine, a cylinder ported for intake and exhaust, a piston reciprocating within the cylinder, a crankshaft driven from the piston, a sleeve valve co-axial with the cylinder and ported for cooperation with the cylinder ports, a valveshaft driven from the crankshaft, a single multi-arm L-shaped driving element transmitting the drive from the valveshaft to the sleeve for imparting thereto a combined reciprocating and oscillating movement, one arm of said element being provided with a laterally extending crank pin, and a ball and socket connection between the sleeve and crank pin.

6. In an internal combustion engine, a cylinder ported for intake and exhaust, a

piston reciprocating within the cylinder, a crankshaft driven from the piston, a sleeve valve co-axial with the cylinder and ported for cooperation with the cylinder ports, a valveshaft driven from the crankshaft, and a multi-arm driving element transmitting the drive from the valveshaft to the sleeve for imparting thereto a combined reciprocating and oscillating movement, one arm of said element extending laterally for connection to the sleeve and another arm extending downwardly from the valveshaft to one side of the crankshaft.

7. In an internal combustion engine, a cylinder ported for intake and exhaust, a piston reciprocating within the cylinder, a crankshaft driven from the piston, a sleeve valve co-axial with the cylinder and ported for cooperation with the cylinder ports, a valveshaft driven from the crankshaft, a bell crank lever intermediate the valveshaft and sleeve and having one arm extending substantially vertically with respect to a horizontal plane containing the valve shaft axis, means connecting said lever with the sleeve, and means for reciprocatingly guiding the movement of said vertically extending arm for imparting to the sleeve a combined reciprocating and oscillating movement.

8. In an internal combustion engine, a cylinder ported for intake and exhaust, a piston reciprocating within the cylinder, a crankshaft driven from the piston, a sleeve valve co-axial with the cylinder and ported for cooperation with the cylinder ports, a valveshaft driven from the crankshaft, and a multi-arm L-shaped driving element transmitting the drive from the valveshaft to the sleeve for imparting thereto a combined reciprocating and oscillating movement, one arm of said element extending laterally for connection to the sleeve and another arm extending downwardly from the valveshaft within the engine crankcase to one side of the crankshaft, and means extending inwardly from the wall of the crankcase for reciprocatingly guiding said last mentioned arm.

In witness whereof, I hereunto subscribe my name this 3rd day of August, A. D. 1928.
